UNITED STATES PATENT OFFICE.

FREDERICK A. WILSON, OF BROOKLYN, NEW YORK, ASSIGNOR TO THE HART & COOLEY COMPANY, OF NEW BRITAIN, CONNECTICUT, A CORPORATION OF CONNECTICUT.

REGISTER.

964,597.

Specification of Letters Patent. Patented July 19, 1910.

Application filed June 17, 1909. Serial No. 502,670.

To all whom it may concern:

Be it known that I, FREDERICK A. WILSON, a citizen of the United States, residing at Brooklyn, county of Kings, State of New York, have invented certain new and useful Improvements in Registers, of which the following is a full, clear, and exact description.

My invention relates to improvements in registers and ventilators, particularly of the type in which a perforated face plate is employed together with a louver or damper at the rear, which latter is to be operated so as to either close the passages through that face plate or open them, said louver or damper performing, when open, the function of a deflector arranged to direct the draft of air through the passages in the face plate.

The invention is of particular utility when ventilation is obtained by means of the blower system, since in such a use it is most important to have effective means for controlling and holding the deflector at any desired angle of adjustment. It is to this feature, namely, the deflector operating and controlling means, that my invention particularly relates.

In the accompanying drawings, Figure 1 illustrates on a small scale and in section my invention, the deflector being partially extended, said section being taken on the plane of the line X—X Fig. 2. Fig. 2 is a front view of a fragment of the face plate and deflector, showing the exposed end of the deflector operating device. Fig. 3 illustrates the connection between the deflector operating device and the deflector, said view being a rear elevation and an edge elevation. Fig. 4 illustrates the deflector operating device, detached.

1 is a perforated face plate of any suitable design. 2 is a damper or louver also of any suitable design. The louver is hinged within a shallow box or frame 3, arranged at the border or near the edge of the face plate 1, and at its rear. The louver 2 when closed prevents the passage of air. When the louver 2 is moved to the position indicated in Fig. 1, it not only opens the ventilator, but also stands obliquely across the direction of the draft, so as to cause the air to be deflected forwardly through the openings in the face plate 1. The means for controlling and operating the deflector 2, in its preferred form, comprises a screw 4, having a

thread of suitable pitch, said screw passing through a nut 5, which is trunnioned or suitably mounted to oscillate or rock in an opening of substantially corresponding size in the louver 2. The front end of the screw 4 has a swivel or universal connection with the face plate or main body of the ventilator. In this particular form of the invention, the screw 4 has a ball-like head 6 arranged in a socket 7 carried by the face plate 1. The socket 7 may be formed in any suitable manner. 8 is a slot in the outer end of the ball-like enlargement 6 suitable to receive a tool like a screw-driver, whereby said screw may be rotated. It will be noted that as the screw is rotated, the nut 5 will travel thereon, and since the latter is connected to the deflector 2, it will impart to the latter a corresponding movement. As the deflector moves away from the face plate 1, the angle 75 of the screw 4 relatively thereto will change, but this is compensated for by the means already described, so that danger of breaking the threads or injuring or disturbing the parts is entirely avoided. By this means the 80 deflector 2 is positively controlled, and all chattering or rattling is avoided. In instances where the blower system is employed, the great necessity of having a positive means for operating the deflector is 85 conspicuously manifest, and it is in such connection that my invention has particular value.

Obviously the design of the various parts may be modified in various ways, and any 90 appropriate means may be provided at the outer side of the face plate to enable the user to manipulate the screw.

What I claim is:

1. In a register or ventilator, a plate having a draft opening therein, a movable damper at the rear thereof, an operating device therefor comprising a screw member, and an intermediate bearing device between said screw member and said damper and relatively movable to both whereby said screw member may oscillate relatively thereto.

2. In a register or ventilator, a plate having a draft opening therein, a movable damper at the rear thereof, an operating device 105 therefor comprising a screw member, and an intermediate bearing device between said screw member and said damper and relatively movable to both whereby said screw member may oscillate relatively thereto and 110

- a swivel connection between said screw and said plate.
3. In a register or ventilator, a perforated plate, a louver therefor at the rear thereof, means to hinge said louver at the rear of said plate, an operating device for said louver comprising a screw, a ball-and-socket connection between said screw and said face plate, the outer end of said ball being exposed for external manipulation, and a nut 10 trunnioned in an opening in said louver, said screw passing through said nut.
4. In a register or ventilator, a perforated

plate, a louver therefor at the rear thereof, means to hinge said louver at the rear of 15 said plate, an operating device for said louver comprising a screw, a ball-and-socket connection between said screw and said face plate, the outer end of said ball being exposed for external manipulation, and a nut 20 carried by said louver and threaded to receive said screw.

FREDERICK A. WILSON.
